UNITED STATES PATENT OFFICE

CHARLES A. FINLEY, OF RUTHERFORD, NEW JERSEY, ASSIGNOR TO BOORUM & PEASE COMPANY, OF NEW YORK, N. Y., A CORPORATION OF NEW YORK

LOOSE-LEAF BINDER

Application filed August 14, 1929. Serial No. 385,704.

This invention relates to the type of loose leaf binder having telescopic leaf-holding posts carried by clamping bars and means for moving the leaf-holding posts in order to bring the posts into or out of locking relation with the leaves.

One of the principal objects of the invention is to provide improved means for locking the leaves in the binder or to unlock the leaves therefrom.

In the drawings:

Fig. 1 is a horizontal section across the posts of a binder embodying my invention, portions of the binder being broken away to show details;

Fig. 2 is a similar section, but showing the leaf-holding posts rotated to the opposite position from that shown in Fig. 1. Fig. 2 is a section on the line 2—2 of Fig. 3, looking in the direction of the arrows;

Fig. 3 is a vertical section of the binder taken through the clamping bars and on line 3—3 of Fig. 2;

Fig. 4 is a longitudinal section through a post of the binder on line 4—4 of Fig. 5;

Fig. 5 is a cross section through the posts of the binder on line 5—5 of Fig. 4, and shows a form of sheet adapted for use in the binder;

Fig. 6 is a view similar to Fig. 5, showing a modified form of sheet.

The invention is shown embodied in a loose leaf binder containing a pair of clamping bars 10 and 11, connected by a telescoping binding post 12 having a threaded screw part 13 and a cooperating sleeve part 14 adapted to vary the distance between the clamping bars. In the embodiment shown in the drawings the screw 13 is mounted in the clamping bar 11, and the sleeve 14, which is the rotatable part, is mounted in the clamping bar 10.

In order to bring the clamping bars together by rotation of the sleeve 14 the end of the sleeve mounted within bar 10 may be slotted at 16 to engage any suitable key to be inserted in the bar 10.

A gear wheel 15 is provided on sleeve 14 and may be housed within the clamping bar 10.

A toothed rack 17 may be housed within clamping bar 10. This rack may have teeth 18 separated into three groups 19, 20 and 21 by lands 22 and 23, to transmit motion from gear wheel 15 to leaf-holding posts 24.

The sheets are mounted on these telescoping leaf-holding posts 24 carried by the clamping bars. Between the clamping bars, the leaf-holding posts are semi-circular in cross-section, each leaf-holding post comprising a semi-circular rod 25 telescoping into a semi-circular tube 26. One end of the rod 25 revolves in clamping bar 11, while the end of the tube 26 is rotatably housed in bar 10 and is provided with a gear wheel 27 within the clamping bar 10. The rack 17 cooperating with the gear wheels 15 and 27 coordinates and synchronizes the movement of the leaf-holding posts and the binding post in the following manner.

The gear wheel 15 of the binding post 12 is adapted to cooperate with the central group 20 of teeth on the rack 17, while the gear wheel 27 of one leaf-holding post is adapted to cooperate with the end group of teeth 19 and the other gear wheel 27 with the other end group of teeth 21.

The relation between the gear wheels and the number of teeth in the groups on the rack is such that when the gear wheel 15 travels over the central group 20 from one land 22 or 23 to the other, each leaf-holding post will make half of a complete revolution, and will be moved from the position shown in Fig. 1 to that shown in Fig. 2, or vice versa.

The lands are so located that they enable the leaf-holding posts to remain stationary after the latter have made their half turn while the binding post is turned further in the direction which caused their half turn. To hold the rack in readiness to move the leaf-holding posts in the opposite direction as soon as the direction of rotation of the binding post is reversed, a spring 28 is provided within each end of the clamping bar 10. When the rack 17 has travelled as far as possible toward either end of the clamping bar, it will bear against and compress the spring at that end.

Plates 29 are provided to close the clamp-

ing bars and retain the movable parts carried by the clamping bars.

A binder embodying the invention is especially well adapted to receive loose sheets or leaves 30 or 30a having open slots 31 or 31a and transverse undercut notches 32, either forming part of the slot (see Fig. 5) or in addition to the slot (see Fig. 6).

The construction of the binder having been described, its operation will now be set forth. Assuming that the parts are in the position shown in Figs. 1 and 5 and that leaves similar to those shown in Fig. 5 are being used, the leaves are not only clamped together by the pressure of the clamping bars, but in addition the half-round leaf-holding posts are fitted into the notches 32 in the leaves in such a way that the leaves cannot be removed from the binder. To unlock the leaf-holding posts and to release the clamping pressure any suitable form of key may be inserted in the slot 16 at the end of the sleeve 14 of the binding post to cause rotation of the binding post sleeve. Rotation of this sleeve acting through the gear wheel 15 causes the leaf-holding posts to make a half revolution, and continued rotation of the key causes continued separation of the clamping bars all in the following manner.

As shown in Fig. 1 the spring 28 is pressing the rack 17 to the right which causes the first tooth of the central group of teeth 20 to interfere with the teeth on the gear wheel 15 of the binding post sleeve. It will, therefore, be obvious that when the binding post sleeve is rotated in a counter-clockwise direction the gear wheel on the binding post shoves the rack to the right until the gear wheel 15 meets the land 22. The parts are now in the position of Fig. 2 of the drawings. It will be observed that the two half-round leaf-holding posts 24 have turned half a revolution on their own axes and have, therefore, unlocked the sheets by coming out of the notches 32 in the sheets. Continued rotation of the binding post sleeve merely causes the teeth on the gear wheel of the sleeve to push the rack 17 against the right-hand spring 28, thus permitting the gear wheel 15 to turn without causing movement of the rack. In this way the binding post sleeve 14 is rotated relatively to the binding post rod 13 and the two clamping bars are separated.

In the similar manner the clamping bars can be brought together and the half-round leaf-holding posts rotated into locking position in the notches 32 of the leaves by rotating the binding post sleeve 14 in the opposite direction. It will be noted that the leaf-holding posts move into or out of operative position with the beginning of rotation of the binding post sleeve.

When leaves 30a (Fig. 6), having the transverse undercut notches 32 facing away from each other are used instead of leaves 30 like

those shown in Fig. 5, an appropriate adjustment is made such as the use of a screw and sleeve having right-handed threads instead of the screw 13 and sleeve 14 with left-handed threads, as shown in Fig. 3, so that rotation of the sleeve 14 in the direction which caused the leaf-holding posts to assume the position shown in Figs. 2, 3 and 6, will cause the binding post to telescope and the clamping bars to be drawn toward each other to clamp upon the leaves.

I claim:

1. A loose leaf binder comprising a pair of clamping bars, in combination with rotatable telescoping leaf-holding posts semi-circular in cross-section, and means for rotating said leaf-holding posts.

2. A loose leaf binder comprising a pair of clamping bars and rotatable leaf-holding posts semi-circular in cross-section carried between the clamping bars, in combination with leaves having transverse undercut notches, and means for rotating said leaf-holding posts into or out of engagement with said transverse undercut notches.

3. A loose leaf binder comprising a pair of clamping bars and rotatable leaf-holding posts semi-circular in cross-section carried between the clamping bars, in combination with leaves having transverse undercut notches, a gear wheel on an end of each leaf-holding post cooperating with a rack to rotate said leaf-holding posts into or out of engagement with said transverse undercut notches.

4. A loose leaf binder comprising a pair of clamping bars, a telescoping binding post joining said clamping bars and rotating telescoping leaf-holding posts semi-circular in cross-section, in combination with means associated with one of the clamping bars for simultaneously telescoping the binding post and rotating the leaf-holding posts.

5. A loose leaf binder comprising a pair of clamping bars, a binding post connected to said bars and adjustable for varying the distance between them, and rotatable telescoping leaf-holding posts semi-circular in cross-section, in combination with means associated with a clamping bar for synchronizing the rotation of the leaf-holding posts with the varying of the distance between the clamping bars.

6. A loose leaf binder comprising a pair of clamping bars, a telescoping binding post and rotatable telescoping leaf-holding posts semi-circular in cross-section, in combination with means associated with a clamping bar for rotating the leaf-holding posts simultaneously with the telescoping of the binding post, and limiting the rotation of said leaf-holding posts to half a revolution.

7. A loose leaf binder comprising a pair of clamping bars, a binding post connected to said bars and adjustable for varying the distance between them, and rotatable tele-

scoping leaf-holding posts semi-circular in cross-section, in combination with means for synchronizing the rotation of the leaf-holding posts with the varying of the distance 5 between the clamping bars, comprising a gear wheel on said binding post, a gear wheel on each leaf-holding post and a rack having alternate groups of teeth and lands adapted to permit continued rotation of the binding 10 post after the leaf-holding posts have ceased to rotate.

8. In a loose leaf binder having a pair of clamping bars, loose leaves each having a slot and transverse undercut notches, a binding 15 post connected to said bars and adjustable for varying the distance between them, passing through the slots in the leaves, and rotatable telescoping leaf-holding posts semi-circular in cross-section, in combination with 20 means for synchronizing the clamping of the clamping bars upon the leaves, and the rotation of the leaf-holding posts into engagement with the transverse undercut notches in the leaves.

25 9. In a loose leaf binder having a pair of clamping bars, loose leaves each having a slot and transverse undercut notches, a binding post comprising a threaded screw and a cooperating threaded sleeve carried by opposite clamping bars, one part of said binding 30 post being rotatably mounted, passing through the slots in the leaves, and rotatable telescoping leaf-holding posts semi-circular in cross-section, in combination with means, comprising a gear wheel on said rotatable part of said binding post, a gear wheel on each leaf-holding post and a rack having alternate groups of teeth and lands, for simultaneously rotating said rotatable part of said 35 binding post for moving the clamping bars from or toward each other and rotating the leaf-holding posts out of or into engagement with the transverse undercut notches in the leaves.

40 45 10. A loose leaf binder having a pair of clamping bars, a binding post comprising a threaded screw and a cooperating threaded sleeve carried by opposite clamping bars, one part of said binding post being rotatably mounted, and a gear wheel on said rotatable part, in combination with telescoping rotatable leaf-holding posts semi-circular in cross-section mounted between the clamping bars, a gear wheel on one end of each leaf-holding post and a rack having groups of teeth separated by lands cooperating with the gear wheels, the relation between the gear wheels on the binding post and the leaf-holding posts and the groups of teeth on the rack 50 being such that when the rotatable part of the binding post is rotated, the leaf-holding posts will make only half a complete revolution.

55 60 65 11. A loose leaf binder having a pair of clamping bars, a binding post comprising a

threaded screw and a cooperating threaded sleeve carried by opposite clamping bars, one part of said binding post being rotatably mounted, and a gear wheel on said rotatable part, telescoping rotatable leaf-holding posts semi-circular in cross-section mounted between the clamping bars, a gear wheel on one end of each leaf-holding post and a toothed rack having groups of teeth separated by lands cooperating with the gear wheels, in combination with leaves having transverse undercut notches, the relation between the gear wheels on the binding post and the leaf-holding posts and the groups of teeth on the rack being such that when the rotatable part of the binding post is rotated, the leaf-holding posts are rotated into or out of engagement with said transverse undercut notches.

In testimony whereof I have signed my name to this specification.

CHARLES A. FINLEY.
